UNITED STATES PATENT OFFICE.

WILLIAM HORROCKS, OF ILION, NEW YORK.

CABINET FOR TYPE-WRITERS OR SEWING-MACHINES.

SPECIFICATION forming part of Letters Patent No. 281,765, dated July 24, 1883.

Application filed October 6, 1882. (No model.)

To all whom it may concern:

Be it known that I, WILLIAM HORROCKS, of Ilion, in the county of Herkimer and State of New York, have invented a new and Improved 5 Cabinet for Type-Writers and Sewing-Machines, of which the following is a specification.

The nature of my invention consists in providing type-writers and sewing-machines with 10 housings composed in part of hinged leaves, which are adapted to be laid in a horizontal position to form a table-top, and having in their outer edges grooves to guide and support the flexible cover when locked in a vertical 15 position by suitable bolts.

Figure 1 is an isometrical perspective view of 20 my improved cabinet. Fig. 2 is a vertical cross-section of a portion of the cabinet and housing. Fig. 3 is a vertical cross-section of 25 the cabinet, showing the grooves for the sliding cover, with the flexible cover removed. Fig. 4 is a horizontal section on line $x-x$ of Fig. 2.

The top of the cabinet C is supported at each 30 end by a series of drawers, and, when the housing is closed, serves as a table-top. The flexible cover A slides in grooves a , cut in the inner surface and near the edges of the wings or leaves B. These grooves continue down- 35 ward through the cabinet-top and terminate in a curve, a' , at the bottom, above plate e, as seen in Fig. 3. The leaves B are hinged at their lower edges to the cabinet-top, and are locked in a vertical position by bolts or catches

35 d. In this position the grooves in the leaves are continuous with the grooves in the lower part of the cabinet, so that by lifting upon the

knob e' the flexible cover readily slides out of the grooves in the leaves into the grooves below from the position shown in Fig. 1 to that 40 shown in Fig. 2. Then by releasing the catches d the leaves may be laid down flat upon the top C, forming extension-leaves, as shown by broken lines B', Fig. 1. In this position the housing is all removed, except a small portion 45 of it, as shown in Fig. 2, which serves as a back to the top of the cabinet. The plates b e serve to protect the lower part of the flexible cover from injury, and the plates b also serve to form a pocket for waste paper, and the 50 leaves B serve the double purpose of supporting the flexible cover when locked in the vertical position, and of a table-top when turned down flat upon the top of the cabinet.

Having described my invention, what I desire to have secured to me by Letters Patent of the United States is—

In a cabinet for the support and protection of type-writers and sewing-machines, a housing consisting in part of the hinged leaves B, 60 provided with the grooves a , and also with the bolt d , for locking them in a vertical position, and in combination therewith the flexible cover A, which is supported by said leaves and adapted to run in said grooves, whereby the hinged 65 leaves serve the double purpose of supporting the flexible cover when locked in a vertical position, and of a table-top when laid down flat upon the top of the cabinet, substantially as shown and described.

WM. HORROCKS.
